US00D571330S

(12) **United States Design Patent** (10) **Patent No.:** **US D571,330 S**
Lee et al. (45) **Date of Patent:** **** Jun. 17, 2008**

(54) **PORTABLE PHONE**

(75) Inventors: **Ki-Eon Lee**, Seoul (KR); **Beom-Ku Han**, Seoul (KR); **Chang-Hwan Hwang**, Goyang-Si (KR)

(73) Assignee: **Samsung Electronics Co., Ltd.**, Suwon-Si (KR)

(**) Term: **14 Years**

(21) Appl. No.: **29/262,102**

(22) Filed: **Jun. 27, 2006**

(30) **Foreign Application Priority Data**

Dec. 28, 2005 (KR) 30-2005-0044322

(51) **LOC (8) Cl.** **14-03**

(52) **U.S. Cl.** **D14/138**

(58) **Field of Classification Search** D14/137, D14/138, 147, 218, 247-248, 341-347; 455/90.3, 455/556.1, 566, 575.1, 575.3, 575.4

See application file for complete search history.
